UNITED STATES PATENT OFFICE.

EDWARD DILL, OF SHELBYVILLE, INDIANA.

CIDER-PRESS.

SPECIFICATION forming part of Letters Patent No. 233,333, dated October 19, 1880.

Application filed August 5, 1880. (No model.)

To all whom it may concern:

Be it known that I, EDWARD DILL, a citizen of the United States, residing at Shelbyville, in the county of Shelby and State of Indiana, have invented a new and useful Improvement in Cider-Presses, of which the following is a specification.

My invention relates to improvements in cider-presses in which a pair of reciprocating plungers operate in conjunction with a pair of reciprocating followers; and the objects of my invention are, first, to provide a pair of strainer-cylinders with a pair of reciprocating plungers; second, to provide each strainer-cylinder with a reciprocating follower or movable pressure-head; third, to afford facilities for the discharge of the pulp after being pressed; fourth, to provide mechanism for moving the followers back into their respective cylinders after the pulp has been discharged. These objects I attain by the mechanism illustrated in the accompanying drawings, in which—

Figure 1 is a top or plan view of the entire device. Fig. 2 is a longitudinal vertical section of the same; and Fig. 3 is a view of part of the operating mechanism at one side of the machine, one side of the frame being removed to show the parts fully.

Similar letters refer to similar parts throughout the several views.

A A represent the two sides of the frame, and A² A² the end pieces. B, B', B², B³, and B⁴ represent cross-pieces let into the side frames, A A. The sides A, ends A², and cross-pieces B are each made in two pieces and all united at the central joint, A³. Thus the frame is composed of a top and bottom half, as shown.

The perforated pressing-cylinders C C' are provided with hoppers D, and each cylinder is securely fastened in the cross-bars B² and B³, the bar B², Fig. 2, being cut away around the cylinders, as at d, to permit the juice to freely pass out. Each cylinder is provided with a long piston, E, and the rear end of each piston is firmly attached to a yoke, P, and on the opposite side of the yoke P from that on which the piston is secured is an extended guide-bar, r, which operates in suitable bearings formed in the cross-bar B⁴, as shown in Figs. 1 and 2. These yokes P are provided with

slide-blocks n n', in which the cranks w w of the crank-shaft M operate, and by means of which the piston receives a reciprocating motion in an alternate manner.

The crank-shaft M is provided with two cranks, w w, diametrically opposite each other, and the shaft M, outside of each crank but inside of the frame A A, is provided with the ratchet-wheels R R', while the shaft M, outside of the frame, on one side, is provided with a wheel, L, which is also provided with a crank-handle, L', by means of which the crank-shaft M is revolved, either by hand or by the gearing of a grinding-mill, (not shown,) which may be located above the press, if desired. 55

The followers G² are piston-heads fitting loosely inside of the cylinders C C'. Each follower-head G² is provided with a rack-bar, G, which extends back and operates in suitable slides formed in the cross-pieces B B'. The outer ends of each rack-bar G is provided with a pin or stop, b, to prevent the head G² from entering the hopper part of the cylinders C C'. Between the cross-bars B and B', 70 and also between the sides A A and longitudinal bar B⁷, are located two independent shafts, J. These shafts are provided with two spur-wheels each, one near each end—that is, the wheel H is secured to the shaft J near the 75 side frame, A, while the wheel H' is secured to the same shaft near the longitudinal bar B⁷ and immediately under the rack-bar G of the cylinder C.

The shaft J is provided with a coil-spring, 80 I, the end i being secured to the side of the wheel H', while the other end i rests against the cross-piece B. Thus, when the wheels H H' are rotated so as to twist or wind up the spring I on the shaft J, the spring will exert a counter power and cause the wheels to rotate back when the force is removed that turned them forward. 85

At each side of the machine, on the inside of the side frames, A A, as shown in Figs. 2 90 and 3, are arranged rack-rods K. The rod K, Fig. 3, is provided with the rack K' on its upper side, and this rack is held in gear with the wheel H³ by the guide T, on which the rod slides freely. Above the rack K' a short distance the rod K is provided with a series of ratchet-teeth, m', in which the projecting lip 100

o of the lever *O'* operates, as will be herein-after described. The upper end of the rod *K*, on the lower side, is also provided with ratchet-teeth *K*², which operate on the ratchet-wheel *R* of the crank-shaft *M*. Above the bar *K* is a spring, *r*, for holding the ratchet-teeth *R*² in gear with the wheel *R*. The wheel *R* is provided on its outer side with a pin or stud, *s*, which, as the wheel *R* revolves, strikes the end of the lever *O'*, carrying it downward, thus releasing the lip *o* from the ratchet *m'*, the use of which will be hereinafter described.

A trough, *U*, with discharge-spout *n*, is located under the perforated cylinders to catch and conduct off the cider.

The operation of my device is as follows, to wit: The ground mass is placed in the hoppers *D D'*, and falls, by its own weight, into the cylinders *C C'* in front of each plunger as the plungers move back. The forward thrust of the plungers compresses the ground mass between the head of the piston *E* and head *G*² of the follower, the follower *G*² and its rack-bar *G* being held forward by the spring *I* on the shaft *J* with sufficient force to squeeze the juice out of the mass of ground apples before it commences its backward stroke. After the juice has been squeezed out of the mass, then the further advance movement of the piston *E* and pulp forces the follower *G*² and its rack-rod *G* back until the pulp is entirely beyond the end of the cylinder. At the same time that the follower is driven back the rack *G* rotates the wheels *H*' and *H*, causing the spring *I* to be twisted up together on the shaft *J*. At the same time the wheel *H* causes the rod *K* to move diagonally upward by reason of the cogs *K*', and the ratchet-teeth *K*² slip over the ratchet-teeth of the wheel *R*, at which point the lip *o* of the lever *O* falls into the ratchet-teeth *m* of the rod *K*, and hold the rod stationary and prevent the spring *I* from acting on the shaft *J* and wheels *H* *H*', thus preventing the follower *G* *G*² from following the piston *E* back into the cylinder until after the pressed pulp *a* has been released and allowed to drop down from between the follower-head *G*² and piston-head *E*. As the wheel *L* and cranks *w* still continue to rotate the pin *s* on the wheel *R* strikes the lever *O*, causing the lip *o* to be released from the ratchet *m*. At the same

time the spring *v* forces the ratchet-teeth *K*² of the rod *K* into gear with the teeth of the wheel *R*, thus preventing the spring *I* from revolving the wheels *H* *H*' and throwing the rod *K* violently back, but allows the rod *K* to be carried back as the crank-shaft and wheel *R* are revolved, the spring *I* aiding the movement and the wheel *H*' carrying the follower forward into the cylinder, where the same operation is again repeated.

It is obvious that the two plungers *E E'* and the two followers act in alternate manner, thus forcing a double-acting continuous press—that is, while one piston is squeezing out the juice the other piston is going back to allow more material to be fed into the cylinder in front of it for pressure.

What I claim as my invention, and desire to secure by Letters Patent, is—

1. In a cider-press, the combination of the cylinder *C*, the piston *E*, the followers *G*², with rack-rod *G*, the wheels *H* *H*', the shaft *J*, the spring *I*, the rod *K*, with rack *K*' at one end and ratchet *K*² at the other end, with ratchet *m* near its middle, the lever *O*, with lip *o*, the wheel *R*, with its pin *s*, and the crank mechanism, substantially as shown and described.

2. In combination, the wheels *H* *H*', the spring *I*, the rod *K*, the spring *v*, the wheel *R*, the pin *s*, and lever *O*, as and for the purpose specified.

3. The combination of the piston *E*, the follower *G*², with rack *G*, the wheels *H* *H*', the shaft *J*, the spring *I*, whereby the wheels *H* *H*' are rotated and the spring *I* wound up as the follower is forced back, as and for the purpose specified.

4. The combination of the rod *K*, the wheel *H*, the lever *O*, the ratchet-wheel *R*, and pin *s*, whereby the wheel *H* is prevented from revolving back until the lever *O* is tripped by the stud *s*, and the wheel *H* revolved by the rotary movement of the wheel *R*, aided by the spring *I*, substantially as shown and described.

In testimony whereof I have signed my name to this specification in the presence of two subscribing witnesses.

EDWARD DILL.
